UNITED STATES PATENT OFFICE.

ANTON WHITNEY, OF RADISSON, WISCONSIN.

METAL CROSSTIE FOR RAILROAD USE.

Application filed April 4, 1927. Serial No. 180,960.

This invention relates to the class of railways and pertains particularly to an improved cross tie structure.

The primary object of the present invention is to provide, in the manner as herein-after set forth, a cross tie which can be ballasted as required to suit various conditions.

Another object of the invention is to provide, in a manner as hereinafter fully described, a railway cross tie formed in sections adjustably connected together to assist in arranging the track rails in proper relation to give the line of a determined gauge.

A further object of the invention is to provide a railway tie having certain novel features of construction which materially expedite the work involved in the laying of a track.

Numerous other objects and advantages of the present invention will become apparent as the description of the same proceeds and the invention will be best understood from a consideration of the following detailed description taken in connection with the accompanying drawings forming a part of the present specification, with the understanding, however, that the invention is not confined to any strict conformity with the showing of the drawings, but may be changed or modified so long as such changes or modifications mark no material departure from the salient features of the invention as expressed in the appended claims.

In the drawings:

Figure 1 shows a tie of the character embodying the present invention, in side elevation.

Figure 2 shows the tie structure in plan view.

Figure 3 is a central longitudinal section through one of the sections of the tie structure.

Figure 4 is a transverse section taken upon the line 4—4 of Fig. 1.

Figure 5 is a detailed perspective view of a novel type of bolt employed for securing a rail flange to a tie section.

Referring now to the drawing in detail, wherein like numerals of reference indicate corresponding parts throughout the several views, the numerals 1 indicate a pair of tie members or sections which, when in operative position, are arranged in spaced end-

opposed relation as shown in Figures 1 55 and 2.

Each of the tie sections 1 is in the form of an elongated casing having a central reinforcing partition 2 depending from the top wall 3 and formed integral with the side walls 4 as shown in Figure 4. This partition is spaced a slight distance above the bottom 5 of the section to permit material which is put in the section as ballast to pass from one end to the other. 60

The top wall of each section upon each side of the partition 2 is provided with the opening 6 which extends transversely of the top in the manner shown and each of these openings has a longitudinal edge formed to set up a guide groove 7, the lower portion of which is flush with the outer surface of the top to permit the insertion between the edges, which are thickened as clearly shown in Fig. 3, of the closure plate 8. 65

Between the filling openings 6 in each side section 1 there is positioned upon the top of the sections and preferably formed integral therewith, a brace device 9, this device being located adjacent one end of the section and having an upwardly extending portion 10 which is designed to engage under the ball of a rail such as that indicated by the numeral 11, when the same is in position transversely of the tie section. 70

The top wall of each tie section is further provided with a short longitudinally extending slot 12 which is spaced a sufficient distance from the base portion of the brace member 9 to permit the positioning of the base of the rail 11 therebetween. 75

Associated with the brace 9 for holding the rail 11 in place, is a bolt 13 of special construction. This bolt 13 comprises the shank portion 14 which is threaded in the usual manner and has a head 15 at one end thereof. Formed integral with the shank, adjacent the head 15 is a relatively long lug 16 rounded at the ends as indicated at 17 and traversed centrally by the bolt as clearly shown in Fig. 5. This lug is designed to fit in the slot 12 to prevent the bolt from turning therein but permits the adjustment of the bolt longitudinally of the tie section as will be clearly understood. 80

When the bolt is in position in a tie section with the lug 16 positioned in the slot 12 in the head or top wall of the section, a

washer device 18 is engaged over the bolt with one edge overlying the base flange of the tie rail 11 as shown in Fig. 3. A locking washer 19 is then placed over the washer 18 and a securing nut 20 engaged on the upper end of the bolt 14 against the slot portion 19 to secure the parts in position.

The tie sections 1 are designed to be connected together by a turnbuckle connection 10 which permits their adjustment relative to one another so that the gage of the track can be accurately obtained. This connection between the tie sections comprises a pair of bars 21 each having one end extended 15 through an adjacent end wall of the tie section shown in Fig. 3. Each of the bars 21 is surrounded at that end which extends through the wall of a tie section by an integral collar 22 which bears against the 20 outer face of the tie section end wall in the manner shown. The end of the rod which projects into the tie section receives thereon a nut 23 which draws the collar 22 securely against the outer face of the wall and thus 25 fixes the rod firmly in position. The opposed ends of the rods 21 are screw-threaded, one opposite the other as shown, and engaging these ends is a turnbuckle 25, which is of the usual construction.

30 From the foregoing description it will be readily understood that when the tie sections 1 are arranged in the position described and connected by the bars 21 and turnbuckles 25, they may be readily adjusted 35 by actuating the turnbuckle 25 to separate or draw together the rails 11 which rest thereon.

It will also be readily seen that ties constructed in accordance with this invention will have all the strength and durability 40 desired and due to the fact that they are hollow, their weight would not be excessive. The means provided for ballasting ties of

this construction is also novel and permits the use of ballasting material which could not be readily used in the usual manner.

Having thus described my invention, what I claim is:

1. A railway tie structure of the character described, comprising a pair of elongated box like sections, designed to be arranged in aligned end-opposed relation each for the support of a track rail, and each having an opening formed through the top thereof to permit the introduction of ballast material thereinto, a cover plate for the opening of each section, a draw bar section extending from each of the opposed ends of the tie sections, and in aligned relation, said draw bar sections each being provided with screw threads upon its free end, and a turn-buckle connection between the said free ends of the draw bar sections designed to assist in shifting the tie sections relative to one another.

2. A railway tie structure of the character described, comprising a pair of elongated box-like sections designed to be arranged in aligned end opposed relation, each for the support of a track rail and each having a pair of openings formed through the top thereof to permit the introduction of ballast material thereinto, a cover plate for each of said openings, in the sections, means arranged between the openings of each rail section for securing an overlying rail thereto, a partition and strengthening plate arranged transversely of the interior of each tie section beneath the surface upon which a rail rests, draw bar members each attached at one end to the inner end of a tie section, and means for connecting said bar members and shifting the same and the attached tie sections, longitudinally and with respect to one another.

ANTON WHITNEY.
